UNITED STATES PATENT OFFICE.

HERBERT T. HERR, OF MERION, PENNSYLVANIA, ASSIGNOR TO WESTINGHOUSE ELECTRIC AND MANUFACTURING COMPANY, A CORPORATION OF PENNSYLVANIA.

TURBINE.

Application filed December 20, 1920. Serial No. 431,929.

To all whom it may concern:

Be it known that I, ROBERT T. HERR, a citizen of the United States and a resident of Merion, in the county of Montgomery 5 and State of Pennsylvania, have invented a new and useful Improvement in Turbines, of which the following is a specification.

My invention relates to elastic-fluid turbines, and more particularly to reversing 10 turbines employing both forward and reverse blading sections, and has for its object to provide apparatus of the character designated in which overheating in an idle section shall be avoided.

15 The single figure of the accompanying drawing is a diagrammatic view of apparatus embodying my invention.

In the operation of marine turbines, for example, trouble is experienced due to the 20 overheating of the ahead section when the astern section is in operation. This arises from the fact that there is a churning of steam in the ahead section which causes the development of a high degree of friction, 25 manifesting itself as heat, and if no way is provided for dissipating this heat, the blading of the ahead section is injured. I, therefore, provide means for the free circulation of steam through an idle section for cool- 30 ing.

Referring to the drawing for a more detailed description of my invention; the turbine shown includes a cylinder or housing 10 and a rotor 11. The ahead blading section is 35 of the single flow combination type comprising an impulse section 12, a high-pressure reaction section 13, and a low-pressure reaction section 14. The astern blading comprises an impulse section 15. Both the ahead 40 blading section and the astern blading section exhaust into the same exhaust chamber 16. The chamber 17 between the high- and low-pressure reaction sections of the ahead section communicates with the exhaust chamber 16 by means of a by-pass 18, a valve 19 being placed in the by-pass to be closed when the turbine is running ahead.

In a marine turbine, having both ahead 50 and astern blading sections exhausting into the same exhaust chamber, when the turbine is running astern, exhaust steam from the astern section enters the ahead section. The steam in the ahead section is then churned about, causing a high degree of friction and

consequently much heat is developed. The 55 blading may be heated to such a high temperature that it will be injured. By providing a by-pass between the hottest part of the ahead section and the exhaust chamber, as shown, exhaust steam from the reversing 60 stage is circulated through one or more ahead stages and tends to dissipate heat in case the temperature of the ahead stage or stages tends to exceed the temperature of the exhaust steam. When the turbine is running 65 ahead, the valve in the by-pass must be closed or else high pressure steam would by-pass the low pressure reaction blading and discharge into the exhaust chamber.

From the foregoing, it will be seen that I 70 have devised a very simple means to prevent overheating of turbine stages when the reverse stage is operative, and it is obvious that the means shown might be applied to reversing stages in case of development of 75 objectionable overheating therein when the turbine is operated ahead.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a turbine, the combination of forward and reversing sections, one of which has a multiplicity of stages, an exhaust connection for the sections, and a by-pass connection between a point intermediate of said multiplicity of stages, whereby, when the latter are running idly, circulation of low-pressure steam through the stages tending to 85 become the hottest is effected.

2. In a turbine, the combination of ahead and reverse blading, a common exhaust connection for the blading, and a by-pass connection affording communication between the 100 exhaust connection and an intermediate portion of the ahead blading whereby, when running reversely, circulation of motive fluid through a portion of the ahead blading and by-pass is created to prevent overheating of said portion of the ahead blading.

3. In a turbine, the combination of a high-

pressure section, a low-pressure section, a reversing section, a common exhaust connection for the low-pressure and reversing sections, and a by-pass affording communication between the exhaust connection and with the space between the high and low-pressure sections whereby, when the reversing section is operative, circulation is established through the low-pressure section to 10 avoid overheating; and a valve in the by-pass to close the latter when the high and low-pressure sections are operative.

4. In a turbine, the combination of an ahead section including a multiplicity of reaction stages, a reversing section, an exhaust connection for the sections, and a by-pass

connection between the exhaust connection and a point intermediate of said multiplicity of reaction stages, whereby, when the latter are running idly, circulation of low-pressure steam is effected from the exhaust connection, through the reaction blading between the exhaust connection and said intermediate point, and through the by-pass connection to the exhaust connection, in order to cool those reaction stages tending to become the hottest when operating idly and in a reverse direction.

In testimony whereof, I have hereunto subscribed my name this 14th day of December, 1920.

HERBERT T. HERR.
